CLAIM

The ornamental design for an acellular dermal matrix sheet allograft, as shown and described.

DESCRIPTION

FIG. 1 is a perspective view of an acellular dermal matrix sheet allograft, showing my new design;

FIG. 2 is a front elevation view thereof;

FIG. 3 is a top plan view thereof;

FIG. 4 is a bottom plan view thereof;

FIG. 5 is a left side elevation view thereof; and,

FIG. 6 is a right side elevation view thereof.

The broken lines in the drawings depict portions of the acellular dermal matrix sheet allograft that form no part of the claimed design.
